DESIGN FOR A BIBLE BOOK COVER

Frank Tatar, Cincinnati, Ohio, assignor to Know
Your Bible Company, Cincinnati, Ohio, a firm

Application September 29, 1944, Serial No. 115,511

Term of patent 14 years

(Cl. D6—2)

To all whom it may concern:

Be it known that I, Frank Tatar, a citizen of the United States, residing at Cincinnati, in the county of Hamilton and State of Ohio, have invented a new, original, and ornamental Design for a Bible Book Cover of which the following is a specification, reference being had to the accompanying drawing, forming part thereof.

The drawing is a perspective view of the Bible book cover showing my new design. The back of the cover is conventionally plain.

I claim:

The ornamental design for a Bible book cover, substantially as shown and described.

FRANK TATAR.
